Attorneys.*

UNITED STATES PATENT OFFICE.

IRA L. PARK, OF WASHINGTON, DISTRICT OF COLUMBIA.

SUSPENSION MEANS FOR ELECTRIC-LIGHTING FIXTURES.

1,394,575.

Specification of Letters Patent. Patented Oct. 25, 1921.

Application filed January 28, 1920. Serial No. 354,627.

To all whom it may concern:

Be it known that I, IRA L. PARK, a citizen of the United States, and resident of the city of Washington, District of Columbia, have 5 invented certain new and useful Improvements in Suspension Means for Electric-Lighting Fixtures, of which the following is a specification.

My invention relates to suspension means 10 for electric lighting fixtures and is designed to provide a suspension of chain form in which the electric conducting wires will be concealed from view.

Chain suspension means as now provided 15 are made up of links of substantially ordinary form with the electric conducting wires interlacing through the links of the chain, and within plain view. This construction is more or less unsightly and it is the object of my invention to provide a link chain suspension means in which the conducting 20 wires are invisible to the eye.

The invention consists of the features and 25 combinations hereinafter described and particularly pointed out in the claims.

In the accompanying drawings:

Figure 1 is a view of an electric fixture, 30 including a link chain suspension means, the electric conducting wires being indicated by dotted lines, these being within the links of the chain.

Fig. 2 is a detail sectional view of several 35 links and the upper hanger or suspension device combined therewith.

Fig. 3 is a sectional view of the two parts 40 of a link separated from each other.

Fig. 4 is a sectional view of eyelets forming 45 a part of my combination.

Fig. 5 is a plan view of a portion of the 40 two members of a link with one of the eyelets in place and in section.

Referring to Fig. 1, 1 indicates generally 45 the upper hanger, 2 indicates generally the chain made up of links and 3 indicates generally the electric lamp fixture which is suspended by the chain.

The links are of substantially ordinary 50 shape and interlace, one with another, substantially as ordinary links of chains do and the conducting wires are concealed within these links, running from link to link and from the upper hanger 1 to the lamp in the fixture 3. These conducting wires are indicated generally by the dotted lines 4 in 55 Fig. 1.

Referring to Fig. 3, the links are made up

of two sections 5, 6, each of which is hollow and of like formation throughout. The half-link 5 is provided with a reduced extension or nipple 7 at its upper end, with a 60 recess in its outer side at 8. This nipple is also recessed at 9. The other end of the half-link 5 is provided with a socket portion 10 of an internal diameter equal to the external diameter of the nipple or reduced extension 7. This socket has a projection 11 on its interior. The socket also has a recess or notch at 12, formed through its wall. The half-link 6 is formed precisely like the half-link 5 but, as shown at 70 Fig. 3, in assembling the two half links they are reversed in position so that the socket portion 10 at the upper end of the half-link 6 will receive the reduced extension or nipple 7 of the half-link 5, and when pressed 75 together the projection 11 on the socket portion will snap in the recess 8 in the nipple and a similar action will take place at the lower end of the link so that the two half-links will be held together.

Previous, however, to snapping the two 80 half-links together, an eyelet such as shown at the left in Fig. 4 at 13, will be placed between the two half-links in the cut-outs or notches 9 and 12 thereof, so that as shown 85 in Fig. 2 this eyelet will be held in place, it being understood that the conducting wires held preferably in one insulated conductor will be threaded through the eyelet and through one of the half-links. The upper link of the series will be combined with the hollow ring link portion 14 of the upper hanger and a nipple or eyelet shown at 15 is arranged at the junction between the upper link and the said hollow ring-shaped 90 portion of the upper hanger, so that the wire conductors will pass through the eyelet 15 from the hollow ring-shaped hanger into the upper part of the upper link, thence through one of the half-links to the lower 100 part thereof, thence up through the eyelet shown at 13, Fig. 2, into the second link, thence through this second link and up through the eyelet into the upper portion of the third link and so on throughout the 105 whole chain.

Fig. 5 illustrates the joint between the lower portion of the half-links, the eyelet being shown in section.

It will be seen from the above that the 110 links when assembled present the appearance of ordinary interlaced links of a chain

and that the conducting wires are completely concealed within the hollow link members.

At the right of Fig. 4 the eyelet is shown 5 with a double flange construction 19 and 20. This eyelet is adapted to be used between the upper part of the first or upper link and the hollow ring-shaped hanger as shown in Fig. 2. The other eyelet shown at the left 10 of Fig. 4 has a flange at the top and bottom and this form of eyelet is adapted for use between links themselves as shown at 13 in Fig. 2.

It will be understood that the illustration 15 and description contained herein is presented in an illustrative way and is not to be regarded as restrictive of the scope of my invention to the particular forms of construction shown, the range of my invention being 20 set forth in the accompanying claims.

It will be observed that the suspension chain as built up with the hollow link members presents the appearance of an ordinary chain and has not the appearance of an imitation construction. The links perform the 25 function of ordinary links in that each link actually forms a support for the following link throughout the chain and the appearance of the chain is not detracted from by the 30 visibility of the electric conductor.

The eyelets serve to protect the wire conductor from abrasion at the points where the wire passes from the link through the openings thereof, and this eyelet may be of insulating material though not necessarily so.

I claim as my invention:

1. A suspension chain for electric lighting fixtures and the like, comprising a series of hollow links, each of which is composed of 40 two sections separable from each other at the center of its upper and lower part where it crosses the adjacent link, with means to hold the separable sections together, and each link having an opening at the point of cross-

ing for the threading of the electric wire 45 from link to link, substantially as described.

2. A suspension chain for electric lighting fixtures, comprising hollow links interlaced with each other, each link being composed of two sections separable from each other at 50 its upper and lower part where it crosses the adjacent link, means for holding the sections together and an eyelet held by and between the meeting ends of the sections of the links, substantially as described. 55

3. A suspension chain for electric lighting fixtures comprising hollow links each being divided at its upper and lower portions where it crosses the adjacent link, one end of one section fitting in a socket in the end of its companion section with means for holding said sections together, openings being provided at the crossing points of the links, through which the lighting wire is 60 threaded, substantially as described. 65

4. A suspension chain for electric lighting fixtures comprising hollow links each being divided at its upper and lower portion where it crosses the adjacent link, one end of one section fitting in a socket in the end of its 70 companion section, with means for holding said sections together, openings being provided at the crossing points of the links, through which the lighting wire is threaded, said means consisting of a projection on one 75 section and a recess on the companion section, so that the sections may be snapped together, substantially as described.

5. In combination in a chain, hollow links, divided at their upper and lower portions 80 where they cross, the ends of the sections thus formed having recesses which match each other, a flanged hollow eyelet held in said recesses, and means for holding the sections together, substantially as described. 85

In testimony whereof, I affix my signature.

IRA L. PARK.
